Primary Examiner — Joseph Kukella*Assistant Examiner* — Darryl J Dardenne(74) *Attorney, Agent, or Firm* — Lowe Graham Jones PLLC(57) **CLAIM**

I claim the ornamental design for a sifting spoon, as shown.

DESCRIPTION

FIG. 1 is a top perspective view of a sifting spoon, showing my new design.

FIG. 2 is a front elevational view of the sifting spoon.

FIG. 3 is a rear elevational view of the sifting spoon.

FIG. 4 is a left side elevational view of the sifting spoon.

FIG. 5 is a right side elevational view of the sifting spoon.

FIG. 6 is a top plan view of the sifting spoon; and,

FIG. 7 is a bottom plan view of the sifting spoon.
